[57] CLAIM

The ornamental design for a combined spray can holder and switch for an air filtering system, as shown and described.

DESCRIPTION

FIG. 1 is a front perspective view of a combined spray can holder and switch for an air filtering system showing my new design;

FIG. 2 is a top plan view thereof;

FIG. 3 is a bottom plan view thereof;

FIG. 4 is a side elevational view thereof, the opposite side being the same as the side shown; and

FIG. 5 is a front elevational view thereof, the rear being plain and unornamented except for two bolt openings therein.

The broken line representation of a support lever in FIG. 1 is for purposes of illustration only.
